Her Attorney

UNITED STATES PATENT OFFICE

MARY E. GILL, OF ST. LOUIS, MISSOURI

ANTITHEFT DEVICE FOR SAFES

Application filed October 20, 1928. Serial No. 313,759.

This invention relates to anti-theft devices for safes and consists of the novel construction hereinafter disclosed.

An object of the invention is to provide a device adapted to be mounted in a safe, having means for spraying the contents of the safe with a distinctive colored fluid, in the event the safe is opened by an unauthorized person and within a period that the safe is set to remain closed.

The full advantages of the construction will be apparent from the following detailed description thereof taken in connection with the drawing in which

15 Fig. 1 is a cross section through the safe showing the device of the invention associated therewith.

Fig. 2 is a vertical section of a portion of the safe illustrating the construction.

20 Figs. 3, 4 and 5 are details of a latch device associated with the mechanism, showing the device in its several positions.

In the embodiment of the invention illustrated in the drawing, the construction is 25 shown associated with a safe 1 having a hinged door 2 controlled by the usual combination lock 3. Within the upper part of the safe, there is a quantity of fluid so controlled that when the safe door is opened by an un- 30 authorized person, within a period of time during which the safe is set to remain closed, said fluid will be sprayed to the lower portion of the safe chamber, and onto the contents thereof to mark the same.

35 The construction consists of a tank supported at the top of the safe, said tank having a filler cap 5. This tank is arranged to contain a fluid, such as red ink, in a sufficient quantity to constitute a source of supply for 40 a spray which is distributed across the bottom portion of the safe below a spray nozzle 6.

It will be understood that the contents of the safe, for example, currency, may be arranged in piles with the separate sheets vertical so that the upper edges will be presented to the spray and will thereby be sprayed. The separate sheets of currency will thus be marked with the identifying fluid, when the device operates under conditions that would 50 result from the unauthorized opening of the

safe door during a time interval for which the safe is set against authorized opening of the door.

The contents of a tank 4 are conducted, under pressure, to the spray nozzle by a conduit 7 that leads through a gear pump 8. The gear pump 8 is actuated by a spring motor 9 which drives a shaft 10, said shaft driving the shaft 11 of the gear pump through a train of speed increasing gearing, comprising a gear 12 on the shaft 10. The gear 12 meshes with a pinion 13 which in turn drives a gear 14, meshing with a pinion 15 carried by the shaft 11 upon which one of the gears 16 of the gear pump is mounted. The gear 14 in turn drives the other gear 17 of the gear pump. This construction last described will be recognized as a standard construction of alarm clocks in which the gear pump shaft corresponds to the operated shaft for the alarm.

It will be unnecessary to enter into the details of construction for controlling the operation of the spring motor that actuates the gear pump, because this is the standard time mechanism of an alarm clock adapted for the release of the spring motor to operate the pump within a predetermined interval of time, determined by the setting of the alarm mechanism. It is sufficient to point to the fact that the spring motor for operating the pump is under the control of a pawl 18 and a ratchet wheel 19. The pawl 18 is carried by a shaft 20 and has an extending arm 21. The shaft 20 is held from oscillating by a detent that will be described hereinafter and which is operated in response to the opening and closing of the safe door.

The shaft 20 is also prevented from oscillating during a time interval by an arm 22 that contacts with an arm 23 on the shaft 20. 90 The arm 22 is arranged to slide into and out of contact with the arm 23, dependent upon the co-ordinated setting of the alarm construction of the alarm clock with the position of the parts as controlled by the time mechanism. By setting the alarm mechanism of the clock mechanism the arm 22 is engaged with the arm 23, thereby preventing operation of the alarm mechanism during the period of time for which the device is set, so 95 100

that the safe door may be opened without operating the pump. When this time passes, by the operation of the time mechanism the arm 21 is brought out of contact with the arm 23 and the spring motor for operating the pump 5 is free to operate. In other words, there are two controls for the operation of the spring motor that operates the pump—the one that is dependent upon the time mechanism, and 10 the other that is dependent upon the position of the safe door. During the time that the time mechanism operates to prevent operation of the pump, the safe door may be opened without the anti-theft device operating, but 15 when the time mechanism is in an interval that the arm 22 is released from contact with the arm 23, the operation of the spring motor for operating the pump is under the single control of the position of the door.

20 This second control comprises a slide bar 24 mounted in supports 25 carried by the sidewall of the safe. The slide bar has an extension 26 extending at right angles thereto, and the extension 26 has an arm 27 at its inner extremity that extends at right angles thereto and into the path of the arm 21 when the slide bar 24 is in rearward adjustment. The slide bar 24 is moved to rearward adjustment against the tendency of a spring 28 by pressure on an angular arm 29 forming a forward extension of the slide bar. The extremity of the angular arm 29 abuts against the inner face of the safe door near its free marginal edge. Thus, when the door is closed, the slide 30 bar is moved backwardly carrying the extremity of the arm 27 across the path of the arm 21, thereby preventing operation of the spring motor. On the other hand, when the door is open, and assuming that the time 35 mechanism is in such a position that the arm 23 is released from contact with the arm 22, the slide bar 24 will move forwardly and move the extremity of the arm 27 out of contact with the arm 21 releasing the spring 40 motor that actuates the pump, so that the same will operate. The operation of the pump draws the fluid from the container 4 and delivers it, under forced pressure, to the nozzle 6 accomplishing the results hereinbefore set out.

50 The construction of the latch device is shown in Figs. 3 to 5, inclusive. The slide bar 24 is formed with a notch having a shoulder 30 and an inclined face 31. The latch bar 32 has a projection therein forming a shoulder 33 and an inclined face 34. The latch bar is mounted for sliding engagement in a support 35 attached to the face of the side wall 55 of the safe. The latch bar is provided at its upper portion with a pin 36 that extends inwardly from the rear face thereof and through the latch bar forming a finger piece extending outwardly from its front face. 60 The slide bar 24 has a notch in its upper edge,

said notch being set in advance of the shoulder 30.

The latch operates as follows: When the door is open and it is desired to hold the slide bar 24 in position so that the extremity of the arm 27 will engage the arm 21 and prevent mechanism from operating, the latch bar 32 is raised until the shoulder 33 engages against the shoulder 30. This prevents the slide bar 24 from moving forward and causes the extremity of the arm 27 to remain in position to intercept the arm 21. After the device is set in this position and the door closed, the slide bar is moved to disengage the shoulders 30 and 33, which causes the latch bar 32 to drop to the position shown in Fig. 4. Thereafter, when the door is open, the slide bar 24 will be drawn forward through the action of the spring 28, and the pin 36 will drop into the notch 37 holding the slide bar from movement and preventing the same from moving rearwardly, whereby the extremity of the arm 27 will be held out of engagement with the arm 21, so that the door cannot be closed to return the slide bar until the latch bar 32 has been again set in the position shown in Fig. 3. It is thus seen that the latch provides means for setting the device to render it inoperative during the period of time that the safe door is open during authorized periods of time. After the door has once been closed, the construction will operate to place the pump motor in operation unless the door is open during the set period of time that the arm 22 engages the arm 23.

55 From the foregoing it will be understood that the construction provides means for protecting the contents of a safe by causing those contents to be identified by spraying over the same an identifying fluid whenever access to the safe is attempted at an unauthorized time by the opening of the safe door.

I am aware that the invention may be modified in certain particulars without departing from the scope of the invention. I do not, therefore, limit myself to the exact invention shown and described but what I desire to claim and secure by Letters Patent is:

1. In a device of the class described, the combination of a safe provided with a hinged door, a fluid container supported within the safe, a supply conduit leading from said fluid container provided with a nozzle for distributing fluid from the tank into the safe chamber, means for advancing fluid from the container to the nozzle, mechanism operated by the door to prevent discharge of liquid when the door is closed and to cause the discharge of liquid when the door is open, and a secondary means preventing the discharge of liquid during a predetermined time interval.

2. In a device of the character described, the combination of a safe provided with a hinged door, a container for supplying liq-

- uid, a spray nozzle connected with said container, a pump between the container and the spray nozzle, a power device for operating said pump, means rendering said power device inoperative when the safe door is closed and releasing said power device for operation when the safe door is open.
3. In a device of the character described, the combination of a safe provided with a hinged door, a container for supplying a liquid, a spray nozzle connected with said container, a pump between the container and the spray nozzle, a power device for operating said pump, means rendering said power device inoperative when the safe door is closed and releasing said power device for operation when the safe door is open, and a secondary means controlled by time mechanism for rendering said power device inoperative during a predetermined time interval.
- 20 4. In a device of the character described, the combination of a safe provided with a hinged door, a container for supplying a liquid, a spray nozzle connected with said container, a pump between the container and the spray nozzle, a power device for operating said pump, mechanism rendering said pump inoperative when the safe door is closed and releasing said power device for operation when the safe door is open, and a latch device for latching said mechanism against operation when the safe door is open and releasing said mechanism by the closing of the safe door.
- 25 5. In a device of the character described, the combination of a safe provided with a hinged door, a container for supplying a liquid, a spray nozzle connected with said container, a pump between the container and the spray nozzle, a power device for operating said pump, means rendering said power device inoperative when the safe door is closed, and to release said power device for operation when the safe door is open, a secondary means controlled by time mechanism for rendering said power device inoperative during a predetermined time interval, and a latch device for latching said means against operation when the safe door is open and for releasing said means when the door is closed.
